Filed Apr. 28, 1969, Ser. No. 16,925

Term of patent 14 years

Int. Cl. D12—14

U.S. Cl. D14—6

FIG. 1 is a side elevational view of the sport car spoiler, showing my new design;

FIG. 2 is a plan view thereof;

FIG. 3 is a front elevation thereof;

FIG. 4 is a rear elevation thereof;

FIG. 5 is a sectional elevation taken along line 5-5 of FIG. 4; and

FIG. 6 is a sectional elevation taken along lines 6-6 of FIG. 4.

The automobile, shown fragmentarily and in broken lines in FIG. 1, is included for illustrative purposes only.

I claim:

The ornamental design for a sport car spoiler, as shown and described.
